UNITED STATES PATENT OFFICE.

WAWRZYNIEC SKRZYNECKI, OF CHICAGO, ILLINOIS.

BLANKING-PRESS.

1,298,806.

Specification of Letters Patent.

Patented Apr. 1, 1919.

Application filed July 1, 1918. Serial No. 242,795.

To all whom it may concern:

Be it known that I, WAWRZYNIEC SKRZYNECKI, a citizen of Poland, residing at Chicago, county of Cook, and State of Illinois, have invented certain new and useful Improvements in Blanking-Presses, of which the following is a specification.

This invention relates to improvements in blanking presses, and particularly to types adapted to operate upon relatively thin material, as paper, cloth or leather, and has as its special object the provision of means whereby a plurality of differently shaped dies are interchangeably mounted upon a rotatable holder so that any desired size may be brought into position for use.

A further object is to provide means whereby the dies are properly centered when brought into operative position, it being understood that the plunger stamps are readily interchangeable within their holders.

These and other like objects are attained by the novel construction and combination of parts hereinafter described and shown in the accompanying drawings, forming a material part of this disclosure, and in which:—

Figure 1 is a side elevational view showing a blanking press made in accordance with the invention, parts being broken away in order to disclose the construction.

Fig. 2 is a similar view of the same looking from the side.

Fig. 3 is a vertical sectional view taken on line 3—3 of Fig. 1.

Fig. 4 is a transverse sectional view taken on line 4—4 of Fig. 1.

Fig. 5 is a side elevational view showing the rotatable die holder.

Fig. 6 is an end view of the same, and

Figs. 7 and 8 are perspective views showing various forms of cutting dies employed.

The press comprises a substantial metallic frame, having a pair of support columns 10 at the front, similar elements 11 being at the rear, all four of which are connected by a transversely disposed frame having sides 12, and end elements 13.

The rear columns 11 extend upward to a level surface 15, while at the front, formed with the columns 10 and horizontal elements

16, are substantially circular disk-like side plates 18 and 19, having a level horizontal top 20.

A cylinder extends inwardly from the frame side 18, through an enlarged circular opening 24 formed in the opposite side 19, its bore 22 being in a horizontal plane.

Mounted on the exterior of the cylinder 22 is a drum 25, the bore 26 of which is in register with the bore 23 of the cylinder. This drum 25 is formed with a plurality of flat longitudinal faces 28, containing openings 29, having beveled side walls adapted to receive the several die blocks 30, formed with similarly beveled side edges 31 and 32, the faces of each of the die blocks having upon them raised cutters 33, formed with sharp edges and containing openings 34 through which the blanked material passes.

These die blocks are adapted to fit neatly within the inclined surfaces of the die holder and may be removed therefrom by pressure from the interior of the cylindrical opening 26 in the center of the drum.

Secured to the extending end of the drum 22 is a ring 35 having ratchet teeth 36 upon its periphery, and engaged upon the frame element 19, rearward of the axial center of the drum, is a lever 38 pivoted upon the screw 39, the lever having in its larger inner end a recess 40, in which is a slidably pawl 41 normally pressed out by the spring 42 at the bottom of the recess, the pawl engaging with the teeth 36 so that the drum 22 may be rotated.

The opposite end of the lever 38 is engaged by a pin 44, to a link or connecting rod 45, its lower end being pivotally engaged at the end of a lever 46 fixed upon a transverse shaft 47 mounted in brackets 48 upon the frame sides 12, the opposite end of the shaft 47 having secured to it a crank 49, terminating in a foot pedal 50, and it will be evident that upon depressing the pedal 50 the lever 38 is caused to oscillate so that the pawl 41 will engage with the teeth 36, thereby transmitting rotary motion to the drum, the lever 38 being normally held in an operative position by the coiled tension spring 51.

Formed through the side plate 18 are

openings 52 arranged in a circular row and agreeing in number and position with the several faces 28 on the drum. Engageable in the openings 52 is the inturned end of a 5 detent lever 53, fulcrumed in a bracket 54 provided with an operating handle 55, so that the same may be retracted from the openings 52, when it is desired to transmit rotary motion to the drum, the detent snapping into position when the next succeeding 10 opening is brought into registration.

Secured on top of the surface 20 is a plate 57, having a raised guard 58 firmly affixed thereabove which is readily removable when 15 it is desired to rotate the drum, the dies 30 extending upward therethrough.

Affixed upon the surface 15 is an upper frame 60, the front portion 61 of which is bored to receive the plunger spindles 62, engaged 20 with a transverse bar 63 at their upper end which is pressed normally upward, due to the coiled compression springs 64, the lower end of the spindles 62 having adjustably secured to them a pressure plate 25 65 having openings in conformity with the die immediately therebelow.

Reciprocating motion is transmitted to the transverse bar 63 by a ring 66 having a lug 67 through which passes a pin 68, the 30 ring being circumjacent to an eccentric 69, fixed to a shaft 70. This shaft is mounted in projections 71 extending up from the bracket 60 at the rear, and a bar 72, formed with a guard arm 73 extending from front 35 to rear of the machine, appropriately curved as at 74 to permit the eccentric to freely rotate.

The lower front end of the arm 73 is formed integral with the guide 61 affording 40 a rigid mounting for the same.

A driven pulley 76 is secured upon the rearwardly extending end of the shaft 70, to which motion is transmitted through the open belt 77 from the driving pulley 78, 45 fixed upon a shaft 79, journaled in bearings 80, mounted upon the end element 13 of the lower transverse frame at the bottom of the machine, the shaft having fixed upon it a driving pulley 81 which may be continuously rotated by a belt 82 from any convenient source of power.

In order to control rotation of the front operative shaft 70, a fixed friction clutch element 85 is secured on a rigid shaft 86, 55 having a part engageable with concave clutch element 87, held to the shaft 79 by a pin 88, operable in a slot 89, formed therethrough and which is slideable by the movement of a lever 90, pivoted on the frame 12 60 on the bracket 91, and drawn normally out of engagement due to the pull of a coiled tension spring 92, this lever being operable by engagement with the foot lever 93 having a pedal 94, the lever being fulcrumed on

the bracket 95, the device being such as engage 65 the friction elements thereby stopping rotation of shaft 70.

From the foregoing it will be seen that when the power is transmitted to the driving pulley 81 and the friction clutches are disconnected, the plungers or spindles will be caused to reciprocate once at each revolution of the shaft 70 pressing whatever material may be held by the guides 58 against the vertically disposed die presented immediately therebelow, forming a blank which will drop through into the cylinder 23 and can be readily removed therefrom.

When it is desired to change the dies, the lever 55 is depressed, the foot pedal 50 operated so as to bring a new die into proper operative position and the plungers changed to correspond.

Having thus described my invention what I claim as new and desire to secure by Letters Patent, is.

1. In a blanking press, the combination with a rigid frame, a cylinder rigidly supported therein, a plurality of faces formed externally on said cylinder, cutting dies engageable with said faces, a pair of plungers mounted to reciprocate vertically over said dies, means for moving said plungers, and a guide adjacent which work may be placed arranged over said dies.

2. In a blanking press, the combination with a rigid frame, a horizontal shaft rotatably mounted at the base thereof, a second horizontal shaft mounted at the upper part of said frame, means for communicating power from one shaft to the other, a pair of vertical plungers mounted on the upper part of said frame, an eccentric on said upper shaft whereby said plungers are given a reciprocative movement, a cylindrical die holder rotatably mounted in the body of said frame, a plurality of interchangeable dies engaged in said die holder, means for rotating said die holder whereby any selected die may be brought into operative position, and means for locking said die holder when in an adjusted position.

3. In a blanking press, the combination with a rigid frame, a die holder mounted therein, said die holder having a cylindrical central opening extending therethrough, a plurality of cutting dies engageable in said die holder, a ratchet fixed upon said die holder, a pawl engageable with the teeth of said ratchets, a foot lever whereby said pawl may be operated and means for locking said die holder when in an adjusted position.

4. In a blanking press, the combination with a rigid frame, a rotatable die holder mounted therein, said die holder having a central cylindrical opening, a plurality of angular faces formed in said die holder, means whereby said dies may be secured

therein, pedally operated means for rotating said die holder, means for locking said die holder when in an adjusted position, a pair of plungers mounted vertically at the head 5 of said frame, a bar connection between the upper ends of said plungers, a ring having a lug engaged with said bar, a shaft rota-

tably mounted at the upper end of said frame, and an eccentric on said shaft operable within said ring whereby said plungers 10 are caused to move reciprocatively.

In testimony whereof I have affixed my signature.

WAWRZYNIEC SKRZYNECKI.
